UNITED STATES PATENT OFFICE.

JOHN M. GOODWIN, OF SAN FRANCISCO, CALIFORNIA.

FIREPLACE WATER BACK.

Application filed August 8, 1921. Serial No. 490,790.

To all whom it may concern:

Be it known that I, JOHN M. GOODWIN, a citizen of the United States, residing at San Francisco, in the county of San Francisco and State of California, have invented new and useful Improvements in Fireplace Water Backs, of which the following is a specification.

This invention relates to water backs for fire places and has for its primary object the provision of a boiler in the back of a fire place, so that, the heat, generated by a heating medium positioned therein, may be utilized to heat a supply of water contained in the boiler to thereby generate steam due to a boiling action of the water, for the purpose of conveying the said steam to a radiator for a secondary heating purpose.

Another object of this invention is to produce a boiler so constructed as to provide a greater heating area for the water contained in the boiler; and to mount on the said boiler conventional means for making the boiler safe and within the scope of city and state regulations.

A further object of this invention is to provide inlet and outlet means for supplying a quantity of water to the boiler and for drawing off a supply therefrom, when so desired.

Other objects and advantages will be apparent during the course of the following description.

Fig. 1 is a front elevation of an open fire-place showing a boiler placed therein,

Fig. 2 is a sectional detail of a boiler,

Fig. 3 is a sectional view through the chimney showing in side elevation my improved boiler and its associated parts.

In the present invention, I propose to employ a boiler designated as a whole by the numeral 25. This boiler embodies in its construction a main body portion 26 and a reduced lower portion 27. On the front face of the portion 27, a plurality of spaced protuberances or extensions 28 are formed, the purpose of which is to allow the water in the boiler to have a greater circulating area so that by entering the protuberances it can be more quickly heated.

The boiler is preferably positioned near

the back wall of the fire place 5 and by being so positioned the reduced lower extremity will present a greater heating surface to the logs or other means used as a heating medium. Adjacent the top of the boiler, I propose to insert an outlet 29 for supplying steam to a radiator. This outlet pipe can conveniently be inserted through the wall of the chimney and then connected to a conventional radiator, whereby a limited amount of heat can be generated when so desired.

Through the back wall of the chimney, I propose to insert an inlet pipe 30 which will serve as a supply pipe for water to be conveyed to the boiler. Adjacent the lower extremity of the boiler a pipe 31 connected thereto serves as an outlet means for carrying off water or an accumulation of dirt that may fall to the bottom of the said boiler.

As shown to advantage in Figures 1 and 3, conventional attachments such as a water gauge 32, a compression gauge 33 and a safety exhaust valve 34 are attached either to the boiler or to the chimney casing, as desired.

It is to be understood that the form of my invention herewith shown and described is to be taken as a preferred example of the same, and that various changes in the shape, size and arrangement of parts may be resorted to without departing from the spirit of the invention or the scope of the claim.

Having thus described my invention, I claim:

The combination with an open fire-place, of a boiler secured to the rear wall of the same, said boiler including an enlarged upper portion and a reduced lower portion, spaced protuberances formed in said boiler, said protuberances having vertical side portions and a horizontal base portion, said protuberances being staggered in relation to those next above, said protuberances being adapted to extend in said fire-place for the purpose of absorbing heat from a fire therein, inlet and outlet means connected to said boiler, and a steam outlet pipe connected to said boiler, substantially as described.

In testimony whereof, I affix my signature.

JOHN M. GOODWIN.
